(57) **CLAIM**

The ornamental design for an attachment for a helmet, as substantially shown and described.

DESCRIPTION

FIG. 1 is a front elevation view of the attachment for a helmet of the present invention;

FIG. 2 is a left-side elevation view of the attachment of the present invention;

FIG. 3 is a right-side elevation view of the attachment of the present invention;

FIG. 4 is a rear elevation view of the attachment of the present invention, the left side view being a mirror image thereof;

FIG. 5 is a top elevation view of the attachment of the present invention;

FIG. 6 is an elevation view of the concave bottom of the attachment of the present invention;

FIG. 7 is a rear perspective view of the attachment of the present invention;

FIG. 8 is a right-front perspective view of the attachment of the present invention;

FIG. 9 is a left-rear perspective of the attachment of the present invention; and,

FIG. 10 is a perspective view of the concave bottom of the attachment of the present invention.
